DIAL RACKING MECHANISM

Clarence W. Minton, Nashville, and John G. O'Hara, Lyle, Tenn., assignors to May Hosiery Mills, Nashville, Tenn., a corporation of Tennessee

Application September 16, 1953, Serial No. 380,502

11 Claims. (Cl. 66—24)

This invention relates to textiles and the manufacture of the same and is particularly concerned with the machinery employed in such manufacture. More particularly the invention relates to a transfer type knitting machine for knitting a complete sock having a ribbed top, plain or ribbed knit leg and foot portions, and a pull top separating adjacent socks.

A knitting machine of the character indicated includes a rotatable cylinder and dial and in accordance with the present invention mechanism is incorporated for racking the dial ahead and angular distance as required in order to produce a non-running welt at the beginning of the ribbed top of the sock.

Heretofore various structures have been proposed and utilized for racking the dials of knitting machines, but such structures have not been completely satisfactory for various reasons including their complexity, the difficulty of obtaining and maintaining their accurate and proper adjustment in order to have proper uniform racking of the dial upon each subsequent operation of the same, with consequent greater and sometimes prohibitive cost of manufacture and maintenance as well as excessive loss of knitting time.

It will be understood that the present invention is applicable to many and different types of knitting machines but for purposes of illustration and without restriction, the invention is illustrated and described in conjunction with a knitting machine of the type illustrated in the patent to W. L. Smith, Jr., et al., No. 2,074,973, of March 23, 1937. Only so much of the knitting machine is illustrated and described as is necessary to afford a clear understanding of the invention, that is, the mechanism for racking the dial and the control means therefor, and reference is had to this patent for any further illustration and description of the basic knitting machine.

Briefly stated, the apparatus of this invention contemplates the application thereof to a knitting machine which for purpose of illustration only, may be of the type disclosed in the above mentioned patent. The dial driving mechanism is modified to the extent of incorporating a differential gearing assembly, the position of the dial with relation to the cylinder being controlled by adjusting the position of the carrier in the differential gearing.

Simple control mechanism, in the form of a cam lobe added to one of the control drums of the knitting machine, a cam follower for contacting such cam lobe, and linkage mechanism for connecting the cam follower to a cam shaft, serves to transmit motion caused by contact of the cam lobe with the cam follower to two or more cams fixed to the cam shaft and engaging cam followers mounted on the carrier associated with the differential gearing. These latter cam followers may be very accurately adjusted in order to control the position of the carrier and consequently the position of the dial with relation to the cylinder in accordance with which

5

cam on the cam shaft is in engagement with the associated cam followers on the carrier.

The normal knitting operations of the machine are in no way affected by the modifications necessary to incorporate the dial racking mechanism of this invention and such mechanism is only utilized during the knitting of the pull top and the beginning of the welt which may comprise approximately two courses of the ribbed top. At the completion of these two or more courses, the dial is racked back to its original position in order to complete knitting of the ribbed top which may be of any desired pattern, but which in this application is disclosed as a 2 x 2 ribbed knit, or in other words, with every alternate two stitches knit on the dial needles a like number of stitches are knit on the cylinder needles. During this operation of course, the cylinder needles located directly below the dial needles remain inoperative. This ribbed knitting operation is conventional and therefore further description thereof is considered unnecessary.

An object of the invention is to apply to a transfer knitting machine utilizing a rotating cylinder and dial, mechanism to rack the dial with relation to the cylinder an angular distance as required to produce the desired rack welt.

Another object of the invention is to incorporate in a transfer knitting machine having a rotating cylinder and dial, dial racking mechanism which involves only slight modification of the conventional knitting machine.

Another object of the invention is the provision in a transfer knitting machine utilizing a rotating cylinder and dial and in which mechanism is provided to rack the dial with relation to the cylinder in order to knit a non-running welt in the ribbed top of a sock, racking mechanism including control means which may be accurately adjusted to obtain the desired angular movement of the dial and which adjustment may be maintained without variation over long periods.

A further object of the invention is the provision in a transfer knitting machine utilizing a rotating cylinder and dial and in which mechanism is provided to rack the dial with relation to the cylinder in order to knit a non-running welt in the ribbed top of a sock, mechanism of more rugged construction in order to minimize breakdowns and consequent loss of knitting time.

Further objects and advantages of the invention will be apparent from the following description taken in conjunction with the accompanying drawings wherein:

Fig. 1 is a front elevation of a knitting machine with the dial racking mechanism of the present invention applied thereto;

Fig. 2, a fragmentary elevation illustrating a portion of the control mechanism for the dial needles of the knitting machine as well as a portion of the control system for the dial racking mechanism;

Fig. 3, a fragmentary elevational view showing in detail a portion of the control system for the dial racking mechanism;

Fig. 4, a fragmentary vertical sectional view showing the dial driving mechanism and the dial racking mechanism incorporated therewith;

Fig. 5, a top plan view of the mechanism shown in Fig. 4;

Fig. 6, a fragmentary side elevational view with parts in section for greater clarity and showing the dial racking mechanism of this invention, as well as a portion of the control means therefore;

Fig. 7, a fragmentary front elevational view with parts in section for greater clarity and showing the dial racking mechanism and control means of Fig. 6;

Fig. 8, a fragmentary front elevational view showing a portion of the knitting machine and the manner of attach-

ment of a portion of the control means for the dial racking mechanism to such knitting machine;

Fig. 9, a fragmentary side elevational view of a portion of the knitting machine shown in Fig. 8 and with parts in section for greater clarity;

Fig. 10, a diagrammatic view showing the relative positions of the cylinder needles and dial needles during the knitting of a 2 x 2 ribbed top; and

Fig. 11, a diagrammatic view similar to Fig. 10 and showing the relative positions of the cylinder needles and dial needles after racking of the dial and during knitting of the non-running welt.

With continued reference to the drawing there is shown in Figs. 1, 2, 4 and 5 a knitting machine including a base 10, an intermediate frame 11 and a base plate 12 carried by the frame 11. Supported on the base plate 12 by suitable bearings is a cylinder 13 rotatably driven by means, not shown, and directly above the cylinder 13 there is disposed a dial 14 which serves to carry and operate dial needles operating in conjunction with needles carried by the cylinder 13 during knitting of the pull top, non-running welt and ribbed top of a sock.

The dial 14 is mounted on a shaft 15 which in turn is carried by a bracket 16 extending from an upright column 17 suitably secured to the base plate 12.

The knitting machine is further provided with suitable means for supporting one or more cones of yarn 18 and yarn guiding means 19 (Fig. 1) is supported by a standard 20 secured to the base plate 12 for guiding yarn to the knitting needles. The knitting machine also has the conventional pattern control mechanism and in the present instance, suitable transfer mechanism for transferring stitches upon completion of the ribbed top from the dial needles to the previously inoperative cylinder needles in order to complete the leg and foot portions of the sock on the cylinder needles only, but since this conventional pattern and transfer control mechanism forms no part of the instant invention no detailed description thereof is believed necessary or desirable.

A shaft 21 extends upwardly through the column or housing 17 and is rotatably supported therein by anti-friction bearings 22. At the upper end of shaft 21 there is provided a spiral gear 23 which meshes with a spiral gear 24 secured to a sleeve 25 rotatably mounted on a shaft 26 which in turn is rotatably mounted in bearings 27 carried by bracket 16. Secured to one end of shaft 26 is a spiral gear 28 which meshes with a spiral gear 29 secured on the upper end of shaft 15 which carries the dial 14.

Also secured to the sleeve 25 at the end opposite the spiral gear 24 is a bevel gear 30 which meshes with diametrically opposed bevel pinions 31 and 32 rotatably mounted on a carrier 33 which in turn is rotatably supported on the shaft 26. Fixed to the shaft 26 and meshing with the bevel pinions 31 and 32 is a bevel gear 34 secured in position on the shaft 26 by a set screw 35 or other suitable means. The bevel gears 30 and 34 secured to the sleeve 25 and to the shaft 26 respectively and meshing bevel pinions 31 and 32, rotatably mounted on carrier 33, provide a differential gear transmission, the purpose and operation of which will be later described.

Carrier 33 is provided with an elongated downwardly extending portion 36 in one side of which is provided a plurality of substantially parallel grooves 37 and 38.

Pivotedly mounted within groove 37 on a pin 39 is a cam follower 40 having a forwardly extending cam engaging nose 41. Pivotedly mounted in the groove 38 on the pin 39 is a second cam follower 42 having a forwardly extending cam engaging nose 43. In order to adjust the position of cam follower 40 with relation to the carrier 33 an adjusting screw 44 is threadedly received in the lower portion 36 of the carrier 33 and projects into the groove 37 into engagement with the rear surface of the cam follower 40. Similarly the cam follower 42 may be adjusted with respect to the carrier 33 by an adjusting screw 45

threadedly received in the lower portion 36 of the carrier 33 and projects into the groove 38 into engagement with the rear surface of cam follower 42.

With particular reference to Figs. 4, 6, 7, 8 and 9 a cam shaft 46 is pivotally mounted on a bracket 47 by means of a threaded stud 48 or other suitable means. Bracket 47 is supported by a bracket 49 which, as shown in Figs. 8 and 9, is supported from a stud 50 carried by housing 17. A shaft 51 serves to carry dial cam control mechanism 52 as well as bell crank levers 53 connected by links 54 to rocker arms 55 having cam followers 56 which engage cams 57 on a drum 58.

The cam shaft 46 is provided with a low cam 59 adapted to engage the cam follower 42 pivotally mounted on the carrier 33 and the shaft 46 also is provided with a high cam 60 adapted to engage the cam follower 40 pivotally mounted on the carrier 33. Additional cams and cam followers may be provided if desired.

In order to control the position of cams 59 and 60 an arm 61 is secured to the cam shaft 46 and is connected by a pivot 62 to a link 63. The link 63 is connected by a pivot 64 to one arm 65 of a bell crank lever 66 mounted on a pivot 67 on a bracket 68 secured to the base plate 12 by screw threaded fastening means or the like 69. The other arm 70 of the bell crank lever 66 is connected by a pivot 71 to a downwardly extending link 72 which, as best shown in Fig. 3, is pivotally connected at its opposite end 73 with a rocker arm 74 mounted by a pivot 75 on the frame 10 of the knitting machine, the rocker arm 74 being provided at its opposite end with a cam follower 76. The drum 58 is provided on one end with an annular flange 77 having secured on the periphery thereof a cam 78 which serves to engage the cam follower 76 for a purpose hereinafter described.

In Fig. 10 there is diagrammatically illustrated the relative positions of the cylinder needles and dial needles during the ribbed knitting operation and in this figure lines 79 represent the operative cylinder needles and lines 80 the inoperative cylinder needles. Lines 81 represent the dial needles all of which are in operation during knitting of the ribbed top. Upon completion of the ribbed top, the dial needles 81 are withdrawn from operation and all of the cylinder needles 79 and 80 are brought into operation to flat-knit the leg and foot portions of the sock.

In Fig. 11 there is diagrammatically illustrated the relative positions of the cylinder and dial needles during knitting of the non-running welt at which time as a result of the racking of the dial by the mechanism above described, the dial needles 81 occupy a position between the operative cylinder needles rather than directly above the inoperative cylinder needles 80 as shown in Fig. 10. The operation of the dial racking mechanism to position the dial needles 81 as shown in Fig. 11, will now be described.

The shaft 21 extending upwardly through the column or housing 17 is driven in a normal manner from the knitting machine and as a result, meshing engagement of the spiral gear 23 with the spiral gear 24 causes rotation of the sleeve 25 and the bevel gear 30 carried thereby. The bevel gear 30 drives the bevel pinions 31 and 32 and since the carrier 33 upon which pinions 31 and 32 are mounted, is held against rotation on the shaft 26, the bevel gear 34 will be driven in a direction opposite to that of the bevel gear 30. Since the bevel gear 34 is fixed to the shaft 26, rotation of such bevel gear 34 will rotate the shaft 15 and dial 14 carried thereby by means of spiral gears 28 and 29.

After the completion of the knitting of the toe-portion of the sock and before rendering the dial needles operative to knit the pull top, the drum 58 and the cam 78 (Fig. 3) are rotated by suitable mechanism to bring the cam 78 into engagement with the cam follower 76 thus pivoting rocker arm 74 about the pivot point 75 and moving the link 72 downwardly. This movement of the link 72 serves to pivot the bell crank lever 66 clockwise (in

Fig. 6), and through the link 63 and arm 61 serves to rotate the cam shaft 46 counterclockwise. Such rotational movement of the cam shaft 46 serves to move the cam 59 with relation to cam-follower 42 and due to the contour of the cam 59 this movement results in the clockwise movement of the carrier 33 and pinion gears 31 and 32 carried thereby about the shaft 26 (Fig. 6). Continued rotational movement of the cam shaft 46 will result in bringing the surface of the cam 60 into engagement with the nose 41 of the cam follower 40, thus retaining the carrier 33 in its advanced clockwise position for as long as the cam 60 is in engagement with the cam follower 40.

Assuming that the bevel gear 30 carried by sleeve 25 is stationary during clockwise movement of the carrier 33, the pinion gears 31 and 32 obviously will rotate with respect to the gear 30 and this rotation will result in the rotation of the gear 34 and shaft 26, an amount equal to two times the angular displacement of the carrier 33. Consequently the dial 14 and needles carried thereby will be moved one and one-third this angular distance. While this operation has been described with the gear 30 and sleeve 25 at rest, obviously the same relative movement of the shaft 26 and dial 14 will take place even though the gear 30 is rotating while angular displacement of the carrier 33 occurs and the resulting movement of its dial needles will of course depend on the gear ratio involved.

The dial 14 remains in its angularly displaced position with the dial needles 81 between the cylinder needles 79 and 80, as shown in Fig. 11, until the pull top and approximately two courses of the ribbed top are completed to knit a non-running welt. At this time, the drum 58 will again rotate to move the cam 78 out of engagement with the cam follower 76, thus permitting counterclockwise pivotal movement of the rocker arm 14 about the pivot point 75, as viewed in Fig. 3, to cause upward movement of the link 72 and consequent clockwise movement of the cam shaft 46, to move the cam 60 out of engagement with the nose 41 of the cam follower 40 thereby permitting the carrier 33 to move counter-clockwise about the shaft 26 to its original position as illustrated in Fig. 6, with the nose 43 of cam follower 42 in engagement with the surface of cam 59.

This permits angular displacement of the dial 14 to its original position with the dial needles 81 located between the operative cylinder needles 79 and above the inoperative cylinder needles 80 to permit conventional knitting of the ribbed top. The exact position of the dial needles 81 with respect to the cylinder needles 79 and 80 during knitting of the pull top and welt and with the dial in racked position is very accurately controlled by the adjusting screws 44 and 45 which position the cam followers 40 and 42 thereby determining the exact angular position of the carrier 33 and dial 14 when the cam followers 40 and 42 are in engagement with either the cam 59 or cam 60 as the case may be. This adjustment may be made for any desired condition and the adjustment will be accurately maintained until such time as it is desired to utilize a different relative position of the dial needles 81.

Obviously the differential gear transmission and control mechanism may be of extremely rugged construction, which will provide accurate control of the relative position of the dial and cylinder needles and which will prevent the necessity for frequent adjustment as well as breakdowns necessitating loss of knitting time with consequent increased costs of production.

It will be understood that the above described dial racking mechanism may be conveniently applied to, or incorporated in, conventional knitting machines by the interposition of the above described differential gear transmission in the dial driving mechanism and by adding the necessary cam to the drum 58 together with the control lever and linkage system for moving the carrier 33, thereby adjusting the position of the dial needles relative to the cylinder needles.

It will be obvious to those skilled in the art that various

changes may be made in the invention without departing from the spirit and scope thereof and therefore the invention is not limited by that which is shown in the drawing and described in the specification, but only as indicated in the appended claims.

What is claimed is:

1. In an automatic transfer knitting machine for the continuous knitting of socks, separated by a pull top and each sock having a non-running welt, a ribbed top and plain or ribbed knit leg and foot portion, dial racking mechanism comprising a sleeve rotatably mounted on the dial drive shaft of said knitting machine, gear means for rotatably driving said sleeve, a bevel gear fixed to said sleeve, a carrier rotatably mounted on said drive shaft, oppositely disposed bevel pinions rotatably mounted on said carrier and meshing with said bevel gear, a second bevel gear fixed to said drive shaft and meshing with said pinions, said first and second bevel gears, said carrier and said pinions providing a differential gear transmission, an elongated arm extending from said carrier, a plurality of cam followers pivotally mounted on said arm, screw threaded means for adjusting the position of each cam follower relative to said arm, a cam shaft rotatably mounted on said machine, a low cam on said cam shaft for engaging one of said cam followers, a high cam on said cam shaft for engaging another of said cam followers, a drum on said machine driven in timed relation to the operation thereof, a control cam on said drum and a control lever and linkage system connected to said cam shaft and operable by said control cam to engage either said high or low cam with the associated cam follower whereby upon engagement of said low cam with the associated cam follower the dial and needles carried thereby will be in position for knitting said ribbed top and upon engagement of said high cam with the associated follower said carrier will be moved angularly and through said pinions will move the dial relatively to the cylinder to knit said pull top and non-running welt.
2. In an automatic transfer knitting machine for the continuous knitting of socks separated by a pull top and each sock having a non-running welt, a ribbed top and a plain knit leg and foot portion, a dial racking mechanism comprising a sleeve rotatably mounted on the dial drive shaft of said knitting machine, gear means for rotatably driving said sleeve, a bevel gear fixed to said sleeve, a carrier rotatably mounted on said drive shaft, oppositely disposed bevel pinions rotatably mounted on said carrier and meshing with said bevel gear, a second bevel gear fixed to said drive shaft and meshing with said pinions, said first and second bevel gears, said carrier and said pinions providing a differential gear transmission, an arm extending from said carrier, cam follower means pivotally mounted on said arm, a cam shaft rotatably mounted on said machine, cam means on said cam shaft for engaging said cam follower means and varying the angular position of said arm and said carrier on said drive shaft, a drum on said machine driven in timed relation to the operation thereof, a control cam on said drum and a control lever and linkage system connected to said cam shaft and operable by said control cam to engage said cam means with the associated cam follower means, whereby said cam means engages the associated cam follower means in one position in which the dial and needles carried thereby are in position for knitting said ribbed top and upon movement of said cam means to a second position said carrier is moved angularly and through said pinions moves the dial relatively to the cylinder to knit said pull top and non-running welt.
3. In an automatic transfer knitting machine for the continuous knitting of socks separated by a pull top and each sock having a non-running welt, a ribbed top and a plain knit leg and foot portion, a dial racking mechanism comprising means rotatably mounted on the dial drive shaft of said knitting machine, gear means for driving said rotatably mounted means, a bevel gear fixed to

said means, a carrier rotatably mounted on said drive shaft, diametrically disposed bevel pinions rotatably mounted on said carrier and meshing with said bevel gear, a second bevel gear fixed to said drive shaft and meshing with said pinions, said first and second bevel gears, said carrier and said pinions providing a differential gear transmission, an arm extending from said carrier, cam follower means pivotally mounted on said arm, a cam shaft rotatably mounted on said machine, cam means on said cam shaft for engaging said cam follower means and varying the angular position of said arm and said carrier on said drive shaft, a drum on said machine driven in timed relation to the operation thereof, a control cam on said drum and a control lever and linkage system connected to said cam shaft and operable by said control cam to engage said cam means with the associated cam follower means, whereby said cam means engages the associated cam follower means in one position in which the dial and needles carried thereby are in position for knitting said ribbed top and upon movement of said cam means to a second position said carrier is moved angularly and through said pinions moves the dial relatively to the cylinder to knit said pull top and non-running welt.

4. In an automatic transfer knitting machine for the continuous knitting of socks separated by a pull top and each sock having a non-running welt, a ribbed top and a plain or ribbed knit leg and foot portion, dial racking mechanism comprising means rotatably mounted on the dial drive shaft of said knitting machine, gear means for rotatably driving said means, a differential gear transmission, a carrier of said transmission mounted on said drive shaft and rotatably carrying opposed gears of said transmission, one of the gears of said transmission being attached to said means rotatably mounted on the dial drive shaft, another of the gears of said transmission being attached to said drive shaft, cam follower means extending from said carrier, cam means mounted on said machine for engaging said cam follower means and varying the angular position of said carrier on said drive shaft, a drum on said machine driven in timed relation to the operation thereof, a control cam on said drum and a control lever and linkage system connected to said cam means and operable by said control cam to engage said cam means with the associated cam follower means, whereby said cam means engages the associated cam follower means in one position of which the dial and needles carried thereby are in position for knitting said ribbed top and upon movement of said cam means to a second position said carrier is moved angularly and through said transmission moves the dial relative to the cylinder to knit said pull top and non-running welt.

5. In a knitting machine of the type in which mechanism is provided for driving a cylinder and a dial in synchronism, means for varying the angular relation between the cylinder and the dial, said means comprising a member rotatably mounted on the dial drive shaft of said machine, gear means for driving said member, a bevel gear fixed to said member, a carrier rotatably mounted on said drive shaft, bevel pinions rotatably mounted on said carrier and meshing with said bevel gear, a second bevel gear fixed to said drive shaft and meshing with said pinions, said first and second bevel gears, said carrier and said pinions providing a differential gear transmission, cam follower means extending from said carrier, cam means mounted on said machine for engaging said cam follower means and varying the angular position of said carrier on said drive shaft, whereby said cam means may be operated to move said cam follower means to vary the angular position of said carrier in order to rack said dial with respect to said cylinder.

6. The structure of claim 5, in which the cam follower means comprises a plurality of cam followers independently and pivotally mounted on said carrier, and said cam

means comprises a low cam for engaging one of said cam followers and a high cam for engaging another of said cam followers, said cams being rotatable simultaneously from a first position in which said low cam engages said one cam follower to a second position after angular movement of said carrier in which said high cam engages said other cam follower to stop further movement of said cam followers and said carrier.

7. Mechanism for varying the angular relationship between a first and second rotating member, in which drive means is employed for transmitting rotation along independent power trains to said first and second members, said mechanism being embodied in a portion of the power train to the second member and comprising a sleeve rotatably mounted on the drive shaft to said second member, a beveled gear fixed to said sleeve, a carrier rotatably mounted on said drive shaft, bevel pinions rotatably mounted on said carrier and meshing with said bevel gear, a second bevel gear fixed to said drive shaft and meshing with said pinions, said first and second bevel gears, said carrier and said pinions providing a differential gear transmission, and means for varying the angular position of said carrier on said drive shaft.

8. The structure of claim 7, said means for varying the angular position of said carrier on said drive shaft comprising cam follower means mounted on said carrier, cam means mounted adjacent to said cam follower means, and means for actuating said cam means in order to vary the angular relation of said carrier on said drive shaft.

9. In a machine for the knitting of socks, dial racking mechanism comprising a differential gear transmission mounted in the power train to the dial drive shaft of said knitting machine, said transmission comprising opposed bevel gears, one connected to drive said drive shaft and the other being rotatably driven from said machine, a carrier, and one or more bevel pinions rotatably mounted on the carrier and meshing with the gears, whereby said dial may be racked by varying the angular position of said carrier.

10. In a machine for the knitting of socks, dial racking mechanism comprising a differential gear transmission mounted in the power train to the dial drive shaft of said knitting machine, said transmission comprising opposed bevel gears, one connected to drive said drive shaft and the other being rotatably driven from said machine, a carrier, and one or more bevel pinions rotatably mounted on the carrier and meshing with the gears, and means for varying the angular position of said carrier whereby said dial may be racked.

11. In a machine for the knitting of socks, dial racking mechanism comprising a differential gear transmission mounted in the power train to the dial drive shaft of said knitting machine, said transmission comprising opposed bevel gears, one connected to drive said drive shaft and the other being rotatably driven from said machine, a carrier, and a pair of oppositely disposed bevel pinions rotatably mounted on the carrier and meshing with the gears, and means for varying the angular position of said carrier with respect to said drive shaft, said means comprising cam follower means mounted on said carrier,

cam means mounted adjacent to said cam follower means, and means for actuating said cam means.
